his attorney.

UNITED STATES PATENT OFFICE.

ALFRED M. LANE, OF ST. LOUIS, MISSOURI.

WEATHER-STRIP.

1,231,621.

Specification of Letters Patent.

Patented July 3, 1917.

Application filed March 20, 1914. Serial No. 826,009.

To all whom it may concern:

Be it known that I, ALFRED M. LANE, a citizen of the United States, and a resident of the city of St. Louis and State of Missouri, have invented a new and useful Improvement in Weather Strips, of which the following is a specification.

My invention relates to weather strips, particularly to that form which is specially adapted for use in connection with windows having swinging sashes, although a weather strip embodying my invention is not restricted in its application to windows of this particular type.

15 The principal object of my invention is to provide a simple and efficient weather strip which will prevent water passing through or being blown through the space between the window and its frame. Further 20 objects are to attain certain advantages which will be more fully set forth herein-after.

The invention consists in the parts and in the arrangements and combinations of parts 25 hereinafter more fully set forth.

In the accompanying drawing, which forms part of this specification, and in which like characters refer to like parts throughout the several views,

30 Figure 1 is a cross-section of a weather strip embodying my invention, showing it applied to the bottom of a casement window, the casement window frame and sash being shown in vertical section and the window being closed;

Fig. 2 is a view similar to Fig. 1, showing a modified form of construction.

In the construction which I have shown in Fig. 1, the weather strip comprises two co-operating members A and B. The member A is formed of a strip of resilient sheet metal which extends along the under face of the bottom rail 1 of the window sash in the rabbet 2. One marginal portion 3 of the member A is fastened by tacks 4 or other suitable fastening means to the bottom rail 1 at the outside or weather edge of the rabbet 2. The marginal edge of the member A adjacent to the marginal portion 3 is bent to form a flange 5, which extends

downward and forms a drip edge. The member A has a body portion 6 which is adjacent to the marginal portion 3 and arches downwardly away from the face of the rabbet 2. The member A thence bends downward and backward toward the marginal portion 3 to form a pocket 7 having a round bottom. The marginal edge of the member A is curled upon itself to form a bead or roll 8. The roll 8 and the body portion 6 form the mouth edges or lips of the pocket 7. When the member A is not in operative engagement with the member B, the roll 8 is in contact or nearly in contact with the body portion 6; and the body portion 6 and the pocket 7 lie spaced away from the face of the rabbet 2.

The other member B of the weather strip is formed of relatively stiff metal and is preferably of extruded metal. The member B is substantially a trough in cross-section, and its inner portion or wall and bottom are fitted in the angle between the sill 9 and the stool 10 and are secured to said sill and stool by screws 11 or other suitable fastening means. The outer portion or wall of the member B is flanged and rounded at its upper edge to form a drip edge 12. This upper edge extends above the lower face of the rabbet 2 into a second rabbet 13. At 80 intervals along the bottom of the outer wall are holes 14 for draining water from the inside of the member B. The inner wall of the member B has at its upper edge, substantially on a line with the top face of the stool 10, a horizontal portion 15 extending outward. At the outer edge of this horizontal portion 15 the inner wall curves upward and backward upon itself to form a groove 16 and a sealing tongue 17. The sealing tongue 17 is slightly curved and inclines upwardly from the groove 16. In the closed position of the window (as shown in Fig. 1) the sealing tongue 17 lies in the pocket 7 and the roll 8 in the groove 16.

The joint between the members A and B is characterized by three lines of contact between the members. The lips of the pocket 7 press tightly against both faces of the sealing tongue 17 and thus form two 100

lines of contact. The roll 8 fits tightly against the bottom of the groove 16 and forms the third line of contact.

The member B may be used with different forms of coöperating members and retain its advantages, and this application is shown in connection with one other form of coöperating member C in Fig. 2. In this construction shown in Fig. 2, the member B is constructed the same and fastened to the sill 9 in the same manner as the member B shown in Fig. 1. The member C which coöperates with the member B is formed of a strip of resilient sheet metal which is reinforced by a sharp rebend 18 at one margin and fastened by tacks 19 or other suitable fastening means to the under face of the bottom rail 20 of the window sash. The body portion 21 of the member C is arched downward away from the bottom face of the bottom rail 20. The other margin of the member C is curled to form a bead or roll 22. The bead 22 engages the round bottom of the groove 16.

25 The outer wall of the member B acts as a shield for the joint between the members A and B and protects this joint against the direct action of water, dust or other weather elements. Any water entering the space between the face of the rabbet 13 in the bottom rail 1 and the upper edge 12 of the outer wall of the member B will tend to flow down along the inside face of this outer wall or drop from the drip edge 5 of the member A. In case any water is forced over the drip edge 5, it will tend to follow the inside face of the inner wall rather than pass the line of contact between the arched portion 6 and the sealing tongue 17. Any water which may pass by the point of contact between the arched portion 6 and the sealing tongue 17 must move upwardly along the sealing tongue in order to pass around its end, and then it must pass two lines of contact before it reaches the inside of the building. The holes 14 drain off the water from the inside of the member B.

Obviously, the weather strip which I have shown and described as an embodiment of my invention may be considerably modified without departing from the spirit of my invention. Therefore, I do not wish to be limited to the particular construction illustrated and described.

55 What I claim is:

1. In a weather strip, a sill member having side walls and a bottom, the outer wall of said sill member being provided with holes therein near said bottom, the inner wall of said sill member being bent to form a groove, one side portion of said groove constituting a sealing tongue, said sealing tongue being below the horizontal plane of the upper edge of said outer wall, and a sash member having a downturned drip edge ad-

jaacent to said upper edge of said outer wall and being bent to form a pocket, adapted to receive said sealing tongue, the free lip of said pocket being arranged to engage the bottom of said groove.

2: A weather strip comprising a trough member adapted to be fastened to the sill of a window and having drain holes therein, the inner side portion of said trough member being bent on itself to form a longitudinal groove near the upper edge thereof, and a resilient sash member bent to form a pocket whose lips are close together, said pocket being adapted to coöperate with said groove and make a tight joint therewith. 70

3. A weather strip comprising a trough member adapted to be fastened to the sill of a window and having drain holes therein, the inner side portion of said trough member having the upper portion thereof projecting outwardly therefrom and bent upon itself to form a longitudinally extending groove, and a sash member having a head adapted to coöperate with said groove and make a tight joint therewith. 80

4. A weather strip comprising a trough member adapted to be fastened to the sill of a window and having drain holes therein, the inner side portion of said trough member having a longitudinal groove near the upper edge thereof, and a sash member having the outer longitudinal edge portion thereof projecting downwardly below the upper edge of the outer side portion of said trough member and near the inner face of said outer side portion, said sash member having a bead adapted to enter said groove and make a tight joint therewith. 90

5. A weather-stripping means for the bottom of a swinging frame, said means comprising a metal frame strip having along its outer longitudinal edge a downwardly projecting flange constituting a drip edge, the inner portion of said strip normally extending farther downward than said flange and being spaced away from the bottom face of said swinging frame, said inner portion of said strip being bent downwardly and backwardly to form an outwardly opening pocket, and a metal sill strip having an inner portion arranged to coöperate with said pocket of said frame strip, the outer marginal portion of said sill strip projecting above said flange of said frame strip and being spaced outside of said flange and out of contact therewith when said strips are in their coöperating position. 105

6. The combination with a window sill having a weather-strip member secured thereto with its outer longitudinal edge portion projecting upwardly, of a window sash having at its bottom a second weather-strip member adapted to coöperate with the inner longitudinal edge portion of said first-mentioned member and having along its 115

outer longitudinal edge a downwardly projecting flange constituting a drip edge, said flange being below said upwardly projecting outer portion of said first-mentioned 5 member and being spaced inside thereof and out of contact therewith in the closed position of said window sash.

Signed at St. Louis, Missouri, this 17th day of March, 1914.

ALFRED M. LANE.
